Filed Mar. 20, 1963, Ser. No. 266,639
7 Claims. (Cl. 336—136)

The field of this invention is that of electrical impedance devices and more particularly that of completely sealed, adjustably variable impedance apparatus.

In attempting to provide high quality tunable radio frequency impedance devices which are effectively sealed against the entrance of foreign matter, including moisture, various configurations have been evolved. The most problematical source of difficulty encountered in the design of such devices is the necessity of a sliding seal, at some point associated with the adjusting means, compatible with electrical accuracy and minimal dimensions. Whether of an axially sliding or a rotating type, these seals are subject to wear and hence deterioration of quality and eventual leakage, and they are further prone to admit or even carry foreign matter through the seal during actual adjustment. In order to reduce these deficiencies, it has been proposed to utilize seals in the form of various conventional bellows and diaphragms by which relative movement can be introduced into a sealed space without sliding contacts. These devices however have disadvantages of their own, being by their nature either limited in the range of adjustment available, or bulky in relation to the space available, or vulnerable at exposed surfaces.

Objects of the present invention are to provide very compact tunable impedance devices suitable for miniature type assemblies, in which the operating parts are completely sealed and which are accurate and reliable in operation to a very high degree; to provide such devices which reproducibly retain dimensional accuracy and remain stable while subjected to wide temperature and humidity variations as well as mechanical and electric shocks; to provide such devices which are adaptable to a broad range of circuitry requirements including a high reactance to resistance ratio, which are well suited for incorporation in printed circuitry, and which are for such purposes electrically and magnetically shielded and stable; to provide such devices whose construction lends itself particularly well to guaranteed quality control and to the utilization of modern dielectric and magnetic materials; and to provide such devices which, although of high quality construction, are of relatively simple and inexpensive manufacture and assembly.

The substance and nature of the invention, for carrying out the above and related objects, may be summarized in some of its characteristic aspects as follows.

A first impedance element, such as a coil or capacitor plate, is attached to an elongate housing near one of its ends where terminals are provided, a second impedance element such as a magnetic core or other capacitor plate, is slidable within, and adjustable from the other end of, the housing with a movement adjacent that end, and a rolling diaphragm, the periphery of which is attached to the housing and the central portion of which is attached to the sliding impedance element seals the impedance elements from the movement.

In a practically important aspect an impedance device according to the invention includes a hollow, cylindrical, transversely divided housing, with the peripheral portion of the rolling diaphragm seal clamped between the two housing parts. The second impedance element is attached to a threaded stem which is part of the movement, and

the central portion of the rolling diaphragm seal is clamped between the second impedance element and the stem. A tuning nut held captive within the housing, and accessible from an end of the housing, threadedly engages the stem, and guide means prevent relative rotation of housing and nut, so that rotation of the nut axially adjusts the impedance elements relative to each other. The movement or adjusting component is located wholly without the sealed housing portion which contains only the impedance elements such that only a single nonrigid sealing element, the diaphragm, is necessary.

These and other objects, inventive aspects, and advantageous results of the invention will appear from the following detailed description of practical embodiments thereof illustrating its novel characteristics.

The description refers to a drawing in which

FIG. 1 is a longitudinal section of a variable inductance device according to the invention;

FIG. 2 is a section on line 2—2 of FIG. 1;

FIG. 3 is a section similar to FIG. 1, of another embodiment of the invention; and

FIG. 4 is a section on line 4—4 of FIG. 3.

The working parts of the device are contained within an elongate housing 11 constructed in two hollow cylindrical parts, a first, impedance sleeve portion 12 and a second, movement sleeve portion 14, which two sleeve portions are adapted to be clamped together end to end as will be described below. The sleeve 14 is externally threaded as shown at 13, for mounting the device through an opening of a panel or similar mounting device between a nut (not shown) and the flange 16 of the sleeve 14, with a transverse face.

In the present embodiment, the impedance device chosen by way of illustration is an inductor. A coil form 21 forms the first impedance element. It has at one end a flange 22 and at the other end a flanged head 23 for mounting it on the sleeve 12. The head flange 23.1 has on the outside a header 24 made of glass and providing a glass to metal seal with the metal ring 25 and the pins 26 and 27. The coil is indicated at 31 and, as shown at 32 and 33, the ends of the coil are joined with the inner ends of the terminal pins 26 and 27. The pins reach through perforations 34, 35 of the coil form head 23 through which they are inserted prior to joining them with the coil leads. After having been assembled separately, the coil form 21 with the coil 31, the header 24 with ring 25, and the pins 26, 27, is secured to the housing sleeve 12 by swaging a lip 38 of this sleeve over the metal ring 25. After swaging, the lip is soldered to the metal ring as indicated at 39, thereby hermetically sealing this end of the impedance sleeve 12 which forms one portion of the housing as a whole.

The adjustable cup core component 41 of the inductor constitutes the second impedance element and consists of a cup-shaped outer portion 42 having a central core 43. The cup core 41 is preferably made of powdered iron and is rigidly attached to a spindle 44 by way of a knurled stud 45 molded thereto. The spindle has two stepped collars 45.1, 45.2 and a flange 46, a neck being formed between the collar 45.1 and the flange 46. Opposite the knurled part 45 a threaded shaft 48 extends from the larger collar 45.2 of the spindle 44.

A metal tuning stem 51 has at one end a disc 52 with a rim 53 reaching beyond the closed end of the cup-core 41, and a perforation 55 which is partly threaded as shown at 56 and which leads into an enlarged bore 57 clearing the collar 45.2. A metal washer 61 is confined between the flange 46 and the large collar 45.2, the flange 46 preferably being formed by swaging the edge of the smaller collar 45.1 over the washer 61. The washer 61 rests in a recess 62 of the powdered iron cup 41, reinforcing the relatively fragile material of the cup itself on

this face. It will be understood that the washer 61 could be a flange that is integral with the spindle 45. The tuning stem has an outside thread 58 and a slot 74 for a screwdriver.

Between the movement sleeve 14 and the tuning stem 51 is inserted a tuning nut 71 which is held captive within the movement sleeve 14 by swaging a portion 72, integral with the movement sleeve, over a taper 72.1 of the closed end of the nut 71. At the opposite open end, the rim of the nut rests against an inwardly extending annular ridge 14.1 of the movement sleeve 14, within a recess 14.2 of the ridge. The swaged fit between the rim 72 of the movement sleeve and the tapered portion 72.1 of the nut 71 is sufficiently loose to permit rotation of the nut within the movement sleeve without permitting longitudinal movement therebetween. The closed end of the nut has a slot 74 for inserting a tool such as a screwdriver. At its open end the tuning nut has a threaded bore 76 which fits and engages the outside thread 58 of the tuning stem 51.

A pin 81, serving as a rotation preventing guide means, is at one, reduced, end 82 pressed into a bore of the disc 52 of the stem 51 and slides in an aperture 84 of the inside ridge 14.1 of the movement sleeve 14. A washer 87 is swaged over the other end of the pin 81 for the purpose to be described hereinbelow.

A rolling diaphragm 91 is provided as a seal between the impedance housing and the movement housing. Seals of this type are formed from rubberized fabric and are commercially available for example under the trade designation "Bellofram." The edge 92 around the central opening of the seal 91 is clamped between the washer 61 on the tuning cup core 41 and the face of the flange 52 of the tuning stem 51. The peripheral rim 93 of the seal is clamped between the flanges 15 and 16 of the impedance sleeve portion 12 constituting an impedance housing and the movement sleeve portion 14 constituting a movement housing, respectively. These flanges and the faces engaging the inner edge of the seal are preferably shaped to form concentric ridges to provide a better seal. The tuning cup core 41 and the tuning stem 51 are assembled by means of the above described threads 48 and 56 and the slot 59 for engaging a screwdriver.

The flanges 15 and 16 are assembled and compressed to confine the outer rim or peripheral portion of the rolling diaphragm seal 91 by means of swaging the rim or lip 16.1 of the flange 16 over the flange 15.

The operation of the above described device is as follows.

Rotation of the tuning nut 71, for example by means of a screwdriver in the slot 74, causes longitudinal movement of the stem 51 which is prevented from rotation by the guide pin 81. The cup core 41 will move longitudinally relatively to the coil form 21 with coil 31. The rolling diaphragm 91 will transfer its cylindrical portion between the inner surface of sleeve 12 and the outer surface of cup 42 during adjustment. The cup 42 thus performs the functions of carrying the seal sleeve and of inductance variation. The rolling diaphragm, in addition to sealing, very effectively assists in preventing rotatory movement between the tuning portion and the movement. The extent of relative longitudinal movement is limited by the washer 87 on the pin 81 which contacts at opposite sides the faces A and B of housing and nut, respectively, at the ends of the travel. The relative movement of the cup core and the coil adjusts the inductance in well known manner, and it will be noted that the relative motion is pure translation without rotation, which is commonly referred to as transverse tuning and is superior to other modes of tuning.

A modification of the above described embodiment is shown in FIGS. 3 and 4. In this embodiment the impedance housing and the tuning components to the left of the rolling diaphragm 191 may be identical with those

described above with reference to FIGS. 1 and 2, whereas the movement components are constructed as follows.

The tuning stem 151 is fastened to the core proper by means of a threaded stud 144. The rolling diaphragm 191 is clamped between the washer 160 and the rimmed flange 152, by means of a nut 153. The stem 151 has a flange 154 pressed against the nut 153 by means of the inside thread of the stem matching the thread of stud 144. The tuning nut 171 has an inside thread 176 which engages the outside thread 158 of the stem 151. The stem 151 has two slots 161, 162 into which extend two ears 163, 164 of the movement housing 114. A stop washer 165 is fastened to the outer end of the stem 151 by means of a screw 166. The tuning nut 171 is secured to the movement housing 114 by means of a swage over rim 172, in the manner described above with reference to the rim 72 shown in FIG. 1.

The operation of this embodiment is similar to that of the device according to FIGS. 1 and 2, as follows. Upon rotating the tuning nut 171 by means of the screwdriver slot 174, the stem 151 is moved in axial direction, with the fixed ears 163, 164 sliding in the axially moving slots 161, 162 of the stem 151 thereby moving the cup core in axial direction without rotation. The inner surfaces of the washer 165 and of the flange 152 respectively, and the faces of the ears 163, 164 serve as stops in the manner described above with reference to the stop element 87.

It will be noted that the above described embodiments of the device according to the invention have several advantages, among others the following especially important ones.

The space within the housing portion 12 containing the sensitive electrical components proper is completely hermetically sealed by the soldering at 39 and the rolling diaphragm 91 firmly clamped between the corrugated flanges 15 and 16, and the washer 61 and the flange 52. It will be evident that these seals can be made with any desired degree of completeness. It will be further noted that the sealing provisions do not in any way increase the overall dimensions of the entire device, which results in very compact exterior dimensioning of the device as a whole.

The cup core 41 with outer shell 42 and inner core 43 fits loosely within the impedance housing 12 which provides ample insulating space between the core and the non-magnetic metal housing, the absence of close proximity of housing and core preventing a lowering the Q value of the impedance circuit due to eddy current losses. The insertion of the insulating diaphragm over the cup core further promotes this favorable effect. Also, since the tuning nut 71 fits the housing part 14 closely and only rotates without longitudinal displacement, foreign particles large enough to foul the engagement between the threads of nut 71 and the stem 51 is with certainty avoided, the outer portion of the nut 71, with the slot 74, completely closing the device on one side similar to the closing of the device on the other side by means of the header 24 within the metal ring 25. The cup core 42 serves several purposes, namely for shielding and favorable impedance regulation, as a plate to which the center of the diaphragm 91 is attached, and as a piston for carrying the diaphragm in all positions, including that when the core is fully extended over the coil as shown in dot and dash lines at 42.1. As well known, diaphragms of the "Bellofram" type should roll off a firm support similar to the side walls of the cup core 41 in order to be preserved in proper shape. The clearance between 12 and 42 is ample for providing the convolution of the diaphragm which is recommended by the makers.

The coil and the core are so designed that the center core 43 is completely withdrawn from the coil 31 while still in engagement with the coil form 21, which provides as wide a range of exact inductance variation as possible.

The amply dimensioned and rigid stop and guidance components securely maintain the above mentioned range

of adjustment, provide the desirable traverse tuning without rotation. The peripheral stiffness of the diaphragm enhances the traverse operation, in addition to its principal purpose of sealing and auxiliary purpose of dielection between metal housing and cup core.

It will be apparent that the sealing and movement features of the above described embodiments can be applied to tunable capacitors, with analogous advantages.

It should be understood that the present disclosure is for the purpose of illustration only and that this invention includes all modifications and equivalents which fall within the scope of the appended claims.

We claim:

1. A variable impedance device comprising:
elongate housing means having a sealed end and an 15 open end;
a first impedance element attached to said housing means near said sealed end, extending into the housing means and distanced therefrom to provide a space between the outside of the impedance element 20 and the inside of the housing means;
a second impedance element mounted on said housing means near its other end for axial displacement relatively thereto and having a portion extending into said space with its outside distanced from said 25 inside of the housing means with clearance peripheral of said space; and
a rolling diaphragm attached at its periphery to said housing means at said open end, having an aperture attached to said second impedance element adjacent 30 said open end of the housing means to seal both impedance elements within the housing means, and extending with its rolling portion into said clearance permitting appreciable relative movement of the two impedance elements.
2. Device according to claim 1 wherein said first impedance element has an axial recess, and said second impedance element has a core member and an outer tube shaped member whose outer surface constitutes said outside of the second impedance element, said axial recess 40 accommodating said core member.
3. Device according to claim 1 wherein said housing means has a movement sleeve portion extending from said rolling diaphragm on the side opposite to said impedance elements, and which device further comprises, 45 within said movement sleeve portion and attached to said second impedance element, means for non-rotatory axial displacement of the second impedance element.
4. A variable impedance device comprising:
a first impedance element; 50
a first tubular housing portion having at one end means for attaching said first impedance element to extend into the housing portion and to seal said end, and having a second end;
a second tubular housing portion having one open end 55 and having at the other end means including a transverse face for attaching it to said second end of the first housing portion;
a second impedance element extending at one side into said first housing portion through said second end 60 and including a stem projecting from the other side into said second housing portion;
a rolling diaphragm having a central opening portion and a peripheral portion that is at said attaching means clamped between said second end of the first 65 housing portion and said transverse face of the second housing portion;
means for clamping said central opening portion of the rolling diaphragm between said other side of the second impedance element, and said stem; and 70
in said second housing portion means for axially adjusting said stem closing said open end and accessible through said open end; whereby the impedance means can be displaced and relatively to each other while they are completely 75

sealed by the diaphragm within said first housing portion.

5. A variable inductor comprising:
a metallic housing including a tubular impedance sleeve and coaxial thereto a tubular movement sleeve, said sleeves each having a flange at adjacent, inner ends respectively, the impedance sleeve having an inwardly extending ridge near its outer end, and the movement sleeve having an inwardly extending ridge near its flange with an aperture therein;
- a coil form assembly including an insulating tube having an open end and a closed end with flanges at each end respectively, an insulating head plate with contact pins leading therethrough and with a metal ring hermetically sealed to its periphery and to the outer end of said impedance sleeve, said closed end of the tube flange being confined between the head plate and said impedance sleeve ridge and the pins extending through the impedance sleeve ridge;
- a coil mounted on said insulating tube and having ends joined to the inner ends of said pins within said impedance sleeve;
- a magnetic cup core including an outer shielding cup and coaxially joined to the bottom of the cup a center core, the space between cup and core fitting said open end flange of said coil form tube, and said cup being dimensioned to provide a space between said shielding cup and the inside of said impedance sleeve;
- a tuning stem assembly including a metallic stem having an outside thread, a threaded central bore and a flange at one end, and a threaded stud fitting said central bore thread and having means for fastening it to said center core at the bottom of the cup core;
- a centrally perforated rolling diaphragm clamped with its periphery between said flanges of said impedance and movement sleeves, and with its central perforation clamped between said cup core bottom and said tuning stem flange by tightening said central bore of the tuning stem, on said threaded stud, the cylindrical portion of said diaphragm being capable of rolling on the outside of said shielding cup in said space between said cup and said impedance housing;
- a tuning nut having an open end with a threaded recess and a closed end with a tapered edge engaged by the rim of said outer end of the movement sleeve swaged over said tapered edge, a shoulder near and facing away from said closed end, said open end resting against said ridge of the movement sleeve, and said threaded recess engaging the outside thread of said tuning stem; and
antirotation guide means including a guide pin fastened to said flange of said tuning stem and fitting said aperture of said inwardly extending ridge of said movement sleeve, and at the end of the pin shoulder means for contacting the corresponding oppositely facing sides of said movement housing ridge and of said tuning nut shoulder.
6. Device according to claim 4 further including:
a guide pin fastened to said stem;
an inwardly extending projection of said second housing portion fitting said guide pin, for preventing relative rotary movement of said stem and said second impedance element;
opposite stop faces on said pin and said housing portion, respectively; and
two opposite stop faces at the end of said pin.
7. Device according to claim 4 further including:
a guide slot longitudinally of said stem,
a guide ear projecting from said second housing portion into said slot, for preventing relative rotary movement of said stem and said second impedance element, and

projections at opposite points of said slot on either side
of said ear providing stops for said ear.
